(57) **CLAIM**

The ornamental design for a condiment storage and dispensing carousel, as shown and described.

DESCRIPTION

FIG. 1 is a top, front perspective view of a combined condiment storage and dispensing carousel showing my new design, the carousel being symmetrical about its central vertical axis and having the same appearance from all sides, the bottom of the carousel being unadorned;

FIG. 2 is a side elevation view thereof;

FIG. 3 is a top, front elevation view of an alternate embodiment of FIG. 1, the carousel being symmetrical about its central vertical axis and having the same appearance from all sides, the bottom of the carousel being unadorned; and, FIG. 4 is a side elevation view of FIG. 3.

1 Claim, 4 Drawing Sheets

FIG. 2

FIG. 3
